UNITED STATES PATENT OFFICE.

HARVEY HUBBELL, OF BRIDGEPORT, CONNECTICUT.

SOCKET-SHELL-CAP FASTENING.

No. 878,634.

Specification of Letters Patent.

Patented Feb. 11, 1908.

Application filed September 5, 1907. Serial No. 391,454.

To all whom it may concern:

Be it known that I, HARVEY HUBBELL, a citizen of the United States, residing at Bridgeport, county of Fairfield, State of Connecticut, have invented a new and useful Socket-Shell-Cap Fastening, of which the following is a specification.

This invention has for its object to provide simple and inexpensive means for attaching the caps to electric socket shells, the essential requirements being that the cap be rigidly secured to the shell, that it be readily removable therefrom when required, that the attachment be easily and quickly made and that the parts lock with a snap when placed in the locking position.

With these and other objects in view I have devised the simple and novel construction which I will now describe, referring to the accompanying drawing forming a part of this specification and using reference characters to indicate the several parts:

Figure 1 is an elevation of an electric socket shell having its cap secured in place by means of my novel fastening; Fig. 2 a view of the cap inverted; Fig. 3 a view of the socket shell inverted; Fig. 4 an enlarged detail sectional view on the line 4—4 in Fig. 1, showing the parts in the locked position; and Fig. 5 is a similar view, the top of the socket shell having been pressed inward to disengage the locking lug from the hole in the cap.

10 denotes an electric socket shell which is made of spring metal and is provided with the usual recess 11 to receive the shank of the socket key (not shown), with two or more ribs 12 (three in the present instance) pressed outward from the metal of the shell in circumferential alinement a short distance below the top of the shell and with an outwardly projecting locking lug 13 located contiguous to recess 11 and to the top of the shell.

14 denotes the cap which is provided at its lower end with an internal circumferential groove 15. The lower wall of groove 15, indicated by 16, is formed by turning the lower edge of the cap inward. This wall is provided with a plurality of recesses 17 (three in the present instance) corresponding in number with the ribs 12 upon the shell and adapted to receive said ribs freely. Above groove 15 and contiguous to one of the recesses 17 is a hole 18 which is adapted to receive the locking lug with a snap engage-

ment. The lower portion of the face of said lug may be beveled off slightly, as at 19, to facilitate the removal of the cap when the locking lug is pressed inward to disengage it from hole 18.

The operation is as follows: When the cap is in place on the shell, to disengage the cap the operator presses inward upon the top of the shell contiguous to the locking lug and to recess 11 sufficiently to disengage the locking lug from hole 18. He then rotates the cap sufficiently to place recesses 17 in alinement with ribs 12 when the cap may be drawn off readily. In attaching the cap, the operator places the cap over the top of the shell with recesses 17 in alinement with the ribs, pressing the cap on until the lower wall of the circumferential groove has passed the ribs and then rotates the cap until the locking lug snaps into hole 18, which locks the cap securely to the shell and renders it impossible to remove the cap without first disengaging the locking lug from hole 18 and rotating the cap or the shell as may be, until recesses 17 and the ribs are in alinement.

Having thus described my invention I claim:

1. The combination with a socket shell having a plurality of external ribs in circumferential alinement and a locking lug, of a cap having an internal circumferential groove at its lower end, the lower wall of which is provided with recesses which receive the ribs freely, and a hole above the groove which is adapted to receive the locking lug with a snap engagement when the ribs are in the groove and the cap is rotated.

2. The combination with a socket shell having in one side a key recess, an outwardly projecting locking lug contiguous to the upper edge and to the key recess, and a plurality of circumferentially alined ribs, of a cap having at its lower end an internal circumferential groove, the lower wall of said groove being provided with recesses to receive the ribs freely, and a hole above the groove which receives the locking lug with a snap engagement.

In testimony whereof I affix my signature, in presence of two witnesses.

HARVEY HUBBELL.
